BY H. J. Fisher ATTY.

UNITED STATES PATENT OFFICE.

EDWARD N. AVERY, OF OBERLIN, OHIO.

COMBINED WAGON-BOX AND RACK.

No. 829,565.

Specification of Letters Patent.

Patented Aug. 28, 1906.

Application filed December 6, 1905. Serial No. 290,564.

To all whom it may concern:

Be it known that I, EDWARD N. AVERY, a citizen of the United States, residing at Oberlin, in the county of Lorain and State of Ohio, have invented certain new and useful Improvements in a Combined Wagon-Box and Rack; and I do declare that the following is a full, clear, and exact description of the invention, which will enable others skilled in the art to which it appertains to make and use the same.

My invention has reference to a combined wagon-box and rack adapted to be used for hauling hay, straw, baskets, barrels, and other articles requiring a wide-spreading base on which to build and also for transporting stock, such as sheep and hogs, all substantially as shown and described, and particularly pointed out in the claims.

In the accompanying drawings, Figure 1 is a perspective view of the invention as used for carrying hay and like bulky loads. Fig. 2 is a cross-section of one side of the rack and its supports and a part of a wagon-body and enlarged as compared with Fig. 1. Fig. 3 is a cross-section on the same line as Fig. 2, except that the side of the rack and the supports therefor are shown as shifted to a different inclination, as hereinafter more fully described. Fig. 4 is a cross-section on line *x*, Fig. 2.

As thus shown, A represents a wagon box or body, say, of any of the common styles and which is provided with the usual cross-pieces *a* at intervals across its bottom, projecting laterally from said bottom and providing supports for the side stays or braces, as ordinarily made. In this instance the usual rigidly-attached braces or standards are omitted and in lieu thereof I employ my new and improved standards or supports B, which serve all the purposes of affixed braces or standards so far as the wagon-box is concerned, but are removably engaged upon said box or body, as shown. Thus each standard has its upper end fashioned with a hook 2, adapted to engage over the upper edge of the wagon-body and lie down on the inside thereof, so as to make a close and effective engagement therewith, while the base of the standard is provided with a pin or projection 3, adapted to seat down in a corresponding hole 4 in cross-piece *a* and extending down below cross-piece *a* to receive a pin or fastener 5 to hold the rack firmly to the body. This makes an effectual side support for the side

of the wagon-body, while it also forms a stable support for the rack, as will now appear. Thus each side of the rack is constituted in this instance of cross-arms C and longitudinal bars D, secured to said arms. Three different arms are shown at each side, corresponding to cross-pieces *a* at the bottom of the wagon-body and mostly from about its middle rearward; but more or fewer might be used, and said arms are omitted at the front of the wagon to afford room for the front wheels to turn without obstruction. In lieu of such arms at the front I employ stay chains or cables E, engaged at one end to the outer edge of each side of the rack and at the other end to upright end frame F at a suitable elevation, and a hinge 6 or its equivalent connects the side frames with the wagon-body at the front. Said chains are adapted to be disconnected at either end.

The arms C are pivotally, but removably, engaged with the corresponding standard B at 7 near the top of said standards on pivot pins or bolts, and separate braces G support each arm from the base of said standards except at the extreme front of the rack over the front wheels, where chains E take the load. The arms C have lateral flanges c along their outer edges, terminating at their upper portions in enlargements having inclined inner edges 8 and outer stops or lugs 9, forming shoulders or abutments for braces G where the sides of the rack are down, Fig. 2. The said braces have ears 11 at their lower inwardly-extending ends, through which they are pivoted in hole 10 at the bottom of the standard by means of suitable pins or bolts and are formed with opposite inwardly-turned jaws 12 at their outer ends, which are slidably engaged over opposite flanges c on arms C and adapted to run to wide-open position on said flanges to the ends thereof over inclines 8 at the outer ends of flanges c and against stop 9 below said inclines, and thus sustaining the sides of the rack in their lay-down position for hay, straw, and the like; but when the said sides are raised to a plane with the sides of the wagon-body, as in dotted lines, Fig. 2, for hauling stock or for purposes requiring such arrangement the braces G run the opposite direction on flanges c to the inner ends thereof, where they remain idle for the time being, (dotted lines, Fig. 2.) The said sides of the rack may then be connected from side to side by chains or other means to hold them together, and flanges c

purposely terminate at 14, so as to allow braces G to be freely removed and replaced. However, there is an intervening or midway adjustment or disposition of the parts, adapted for any use requiring such half-way-raised position, and in which the lower ends of braces G have been taken from engagement through holes 10 to holes 15 near the central top portion of standard B. The same pins or bolts 10 are used here as at the lower end of the standards, and shoulders 16 outside of and below the plane of said holes 15 serve as rests for braces G, which have their inwardly-extending ends 11 bearing thereon at their base or shoulders. This provides for a substantially forty-five-degree angle of inclination for the sides of the rack, which frequently is desirable and which is accomplished by merely moving braces G from holes 10 to holes 15 in standards B, as just described. In either case, whether brace G be engaged on the standard at hole 10 or at hole 15, its shoulder or offset 15 rests down on a corresponding shoulder on said standard outside its own pivot.

25 What I claim is—

1. In a combined wagon-box and rack, a standard having its upper end bent inwardly into hook shape engaged over the edge of the wagon-box and having a downward projection on its lower end and a shouldered offset at its middle portion and a pivot-hole behind said shoulder, in combination with a rack-supporting arm pivoted to the top of said standard and a brace adapted to slid-

ably engage the outer edge of said arm and 35 pivoted at its inner end on said standard and constructed to be engaged through said pivot-hole and rest on said shouldered offset in an inclined position.

2. The wagon-box and the rack thereon, in 40 combination with standards having hooked ends engaged over the sides of said box and supported at the side thereof at their bottom, in combination with braces slidably engaged with the sides of said rack and adapted to be 45 adjustably engaged with said standards at different elevations at their inner ends, said standards provided with pivot-holes for said braces at their points of engagement with the standards and shoulders for the braces to rest 50 upon outside said pivot-holes.

3. The wagon-box and standards hooked over the sides thereof at their top having pins at their bottom engaged in side projections from said box, in combination with the rack 55 having arms pivoted on said standards and adjustable braces between said standard and arms, said arms having inclined inner edges at their outer ends and stop-lugs on their bottom beneath said inclined edges and said 60 braces constructed to engage said edges and lugs.

In testimony whereof I sign this specification in the presence of two witnesses.

EDWARD N. AVERY.
